United States Patent

Des. 241,895
Patented Oct. 19, 1976

241,895

CONTAINER FOR DISPLAY ARTICLES, PAPERS, AND DOCUMENTS

Charles H. Forbes, 585 Clover Hills Drive,
Brighton, N.Y. 14618

Filed Apr. 28, 1975, Ser. No. 572,458

Term of patent 14 years

Int. Cl. D6—04

U.S. Cl. D6—85

FIG. 3

FIG. 1

FIG. 2

FIG. 5

FIG. 6

FIG. 1 is a front elevational view of a container for display articles, papers, and documents in erected condition, showing my new design;

FIG. 2 is a right elevational view thereof;

FIG. 3 is a left elevational view thereof;

FIG. 4 is a top plan view thereof;

FIG. 5 is a rear elevational view thereof; and

FIG. 6 is a bottom plan view thereof.

I claim:

The ornamental design for a container for display articles, papers, and documents, substantially as shown.
